UNITED STATES PATENT OFFICE.

WILLIAM CUMMING SKINNER, OF VANCOUVER, BRITISH COLUMBIA, CANADA.

BRACKET.

Application filed April 11, 1927, Serial No. 182,939, and in Canada May 13, 1926.

My invention relates to improvements in brackets, the objects of which are to provide means whereby bearers for scaffolding shelves and the like may be securely held to walls which are to be covered with plaster or stucco, and which bearers for temporary scaffolding may be quickly removed. Further objects are to provide a bracket which is economical in use and which is of adequate strength for any of the duties imposed upon it.

The invention consists essentially of a strip of metal having a semi-cylindrical medial portion which is slotted to receive one end of a suitable bearer, as will be more fully described in the following specification in which:—

Fig. 1 is a front view of the invention.

Fig. 2 is a plan view showing a bearer in position.

Fig. 3 is a general view of the invention as applied to a wall to be plastered and showing a bearer (in dotted line) in the slot.

In the drawings like characters of reference indicate corresponding parts in each figure.

The numeral 1 indicates a wall surface of ship-lap though the device is applicable equally well to a wall of any other construction, to which the bracket generally indicated by the numeral 2 is nailed as at 3. The bracket 2 is formed of a strip of metal 4 having a semi-cylindrical portion 5 of such projection as to be easily covered by the finish coat of plaster or stucco. The portion 5 is provided with a slot 6 extending downwards from its upper extremity for the greater portion of its length, the slot 6 being preferably of somewhat less width than the bearer 7 to be fitted thereto, so that as the bearer is pressed down into the slot the edges of the strip are caused to cut slightly into the wood of the bearer in extent according to the pressure exerted by the metal from which the bracket is made and to grip the bearer firmly at its lower edge and sides. Obviously in scaffolding or temporary work, the outer end of the bearer is suitably supported to bear its part of the superposed load. In scaffolding a wall to be

plastered or coated with stucco, see Figure 3, 50 the ship-lap wall 1 is strapped with vertical strapping 8 which is in turn covered with laths 9 the laths being butted up close to the bracket 2 as at 10, the first coat of plaster is then applied as at 11, the plaster being 55 brought close up to the scaffold bearers 7. When the first or rendering coat of plaster has been applied the floating or rough cast coat is put on, starting from the top of the wall and working downwards in the usual 60 way. As each row of brackets 2 are reached the scaffolding is removed and the bearers 7 are detached from their outer supports and as a downward pull is exerted upon them their hold in the slots 6 will be broken, permitting 65 them to be removed without difficulty. It then suffices to fill in the semi-cylindrical portion and the slot of the bracket with cement or plaster and to continue the floating coat 70 completely covering the bracket from view. When the brackets are used for shelving or other permanent work the upper edge of the bearer is preferably skew nailed to the wall and the plaster brought down into contact therewith, when sufficient hold is provided to 75 hold the bearer against removal.

It will thus be seen that I have invented a bracket for scaffolding or shelving which is simple and economical in manufacture and which is easily secured to a wall surface and 80 capable of securely holding a suitable bearer without extraneous fastenings.

What I claim as my invention is:

The combination with a scaffold bearer or the like, of a bracket adapted for attachment 85 to a wall surface, said bracket being formed of inherently springy sheet material and having medial portions curved away from the wall surface to define a vertical slot into which the end of a bearer is adapted to be 90 supported, said slot being of a width less than that of the bearer whereby, said medial portions are caused to exert a resilient gripping pressure on the side of the bearer.

Dated at Vancouver, B. C., this 5th day of 95 April, 1927.

WILLIAM CUMMING SKINNER.
